UNITED STATES PATENT OFFICE.

RICHARD D. FARRELL, OF TYRONE, PENNSYLVANIA.

AUTOMATIC SAFETY APPLIANCE FOR RAILWAYS.

No. 911,961.

Specification of Letters Patent.

Patented Feb. 9, 1909.

Application filed June 4, 1908. Serial No. 436,715.

To all whom it may concern:

Be it known that I, RICHARD D. FARRELL, a citizen of the United States, residing at Tyrone, in the county of Blair and State of Pennsylvania, have invented a new and useful Automatic Safety Appliance for Railways, of which the following is a specification.

The invention relates to improvements in automatic safety appliances for railways.

The object of the present invention is to improve the construction of safety appliances for railways, and to provide a simple and comparatively inexpensive safety appliance, adapted to be easily installed on railroads, and capable, should an engineer attempt to pass under a danger signal without stopping, of automatically venting or bleeding the train pipe of the air brake system and of sounding the whistle signal within the cab of the locomotive, and of displaying or lighting an electric light in front of the engineer, so that the engineer if alive will have his attention called to the danger signal, and if dead, will have his engine stopped by a complete application of the brakes.

A further object of the invention is to provide a safety appliance of this character adapted to maintain the air brake bleeding valve in an open position until the train is brought to a standstill, and capable of then automatically re-setting itself and of permitting the brake valve to close.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is an elevation, partly in section, of a safety appliance, constructed in accordance with this invention, the tripping device being arranged in the path of the oscillatory valve opening lever. Fig. 2 is a similar view, illustrating the manner of operating the valve opening lever. Fig. 3 is a transverse sectional view. Fig. 4 is an enlarged detail sectional view of the

air brake bleeding valve. Fig. 5 is an enlarged detail view, illustrating the construction of the joint of the pivoted member of the tripping device.

Like numerals of reference designate corresponding parts in all the figures of the drawings.

1 designates an air brake bleeding valve, movable vertically within a valve casing, which is connected to a pipe 2 in communication with the train pipe, whereby when the valve is opened, as hereinafter explained, pressure in the train pipe will be reduced for applying the air brakes. The pipe 2, which is arranged vertically, has its upper end 3 threaded for the reception of a nipple 4, which is interiorly and exteriorly threaded, as clearly illustrated in Fig. 4 of the drawings. The nipple connects the valve casing with the pipe 2 and the said valve casing is composed of upper and lower sections 5 and 6. The lower section 6, which is in the form of a cap, is interiorly threaded and engages exterior screw threads 7 of the lower end of the upper section of the casing. The said lower section 6 is also provided with a reduced depending interiorly threaded portion 8, which screws on to the nipple 4. The upper section is provided with a vertical bore or opening 9, having its lower portion enlarged and tapered to form a seat for the valve 10, which is tapered as shown. The upper portion of the valve is also provided with transverse discharge passages 11, through which the air escapes when the valve is open. The valve, which is movable vertically, is provided with an upwardly extending valve stem 13, and it has a recess 14 in its lower face for the reception of the upper end of a vertically disposed spiral spring 15, seated on the lower section of the casing and adapted to hold the valve 10 normally in its closed position. The spring also operates to automatically close the valve after the latter has been operated and released by the mechanism hereinafter described.

The valve is mounted within a supporting bracket consisting of a collar 16 and upwardly extending arms 17, having their upper terminals bent horizontally and secured to the top of the cab, as clearly illustrated in Fig. 3 of drawings. The top 18 of the cab 19 is provided with an opening, and the valve

casing is equipped with a pair of upwardly extending arms 20, extending through the opening and forming a support for a double acting oscillatory lever 21.

5 The lever 21, which extends above the top of the cab, is provided at its lower end with a pair of spaced downwardly extending projections 22, normally located at opposite sides of the valve stem 13, as illustrated in 10 Fig. 1 of the drawings, whereby the valve stem will be depressed and the valve opened, when the lever is moved in either direction in a perpendicular position. The lower end of the vertical lever is provided between the 15 projections 22 with a comparatively curved edge 23, forming a recess and providing opposite cam portions for actuating the valve stem. The valve stem is provided in its upper end with a seat or recess 24, and when 20 the lever is oscillated, one of the projections 22 is carried to a point directly beneath the pivot 25 of the lever 21, as illustrated in Fig. 25 of the drawings. In this position such projection or pointed portion 22 engages the seat or recess 24 of the upper end of the valve stem, and the combined pressure of air and the coiled spring 15 is sufficient to maintain the lever in engagement with the upper end of the valve stem, whereby the valve will be 30 held open until the train is stopped. When the air pressure within the train pipe is reduced sufficiently to effect a complete application of the brakes and stop the train, the lever 21 is automatically returned to its perpendicular position by means of opposite 35 coiled springs 26, located in advance and in rear of the lever 21 and arranged at an inclination. The springs 26 are secured at their lower ends to the top of the cab, and their 40 upper ends are attached to the lever 21. When the lever is moved either backwardly or forwardly from a perpendicular position, one of the springs will be distended and will 45 operate to return the lever to its vertical position as soon as the lever is free to move.

The lever 21 is equipped at its upper end with a horizontally disposed substantially oblong loop 27, having curved end portions and preferably constructed of a single piece 50 of metal, the terminals of which are bolted, or otherwise secured to the upper end of the lever 21. The loop, which projects laterally upon the lever in each direction a considerable distance, is provided for enabling tripping devices in different vertical planes to be 55 employed for operating the safety appliance.

The safety appliance is operated by a tripping device, consisting of a lever 28, fulcrumed at an intermediate point by a bolt 29, or other suitable fastening device to a bracket 30, or other suitable support. The inner arm 31 of the tripping device is provided with a slot 32 and is connected by a 60 bolt 33, or other suitable fastening device

70 with a rod or bar 34, which is connected with a pivoted semaphore 35. The semaphore is operated in the usual manner by operating mechanism including a rod 36 and a bell crank lever 37, fulcrumed at its angle and having one of its arms connected with the rod 34 by a slot and pin connection, as shown at 38. The tripping device may be connected with a semaphore, or other signal in any other preferred manner, as will be readily understood. When the semaphore is raised to display it, the tripping device is swung downward into the path of the valve operating lever, and should a train attempt to run past the signal, the loop of the lever will 80 come in contact with the tripping device and the valve will be opened and locked in such position, as before explained.

85 The lever engaged arm 39 of the tripping device is approximately U-shaped and is provided with a hinged side 40, pivoted at 41 and depending below the opposite side of the U-shaped arm or portion, as clearly shown in Fig. 1 of the drawings. The pivoted member 90 when in operative position is arranged at an inclination, and its upper end is reduced to fit in a slot or perforation of the body portion of the lever, suitable shoulders being provided at the joint for limiting the inward movement of the pivoted side or member. 95 The hinged side is yieldably held in operative position with relation to the rest of the tripping lever by means of a coiled spring 42, connected with the pivoted side 40 and with the opposite side, the sides of the U-shaped 100 arm or portion being equipped with eyes or other suitable means for the attachment of the ends of the spring. The coiled spring 42 is of sufficient strength to secure an operation of the lever 21, and when the lever has 105 reached the limit of its movement, the tripping device permits the said lever to pass beyond it, whereby breakage of the parts is prevented. The upward movement of the pivoted side 40 of the tripping lever is limited 110 by means of a lug or projection 43, extending from the body portion of the lever and located at the outer side and above the pivoted side or member 40, as clearly shown in Figs. 1 and 2 of the drawings. When the semaphore 115 is dropped, motion is communicated to the tripping device, which is swung upward out of the path of the lever 21. The movement of the lever 21 from a perpendicular position is limited by means of a pair 120 of downwardly diverging arms 44, located in advance and in rear of the pivot 25 and extending downward therefrom and terminating in advance and in rear of the projections 22. The valve casing operates as a stop and is 125 engaged by the arms 44 for limiting the movement of the lever 21, and the lower ends of the said arms 44 are provided with heads 45 having rounded edges and adapted to operate push buttons 46 of an electric circuit 47 130

The electric circuit 47 includes a suitable battery 48 and an electric light 49, mounted in the cab in front of the engineer. The push buttons are mounted in suitable supports 50, which are carried by the bracket 16, and the lever 21 when at the limit of its movement in either direction is adapted to hold one of the push buttons in a depressed position for maintaining a closed circuit. The 10 light will indicate to the engineer that the safety appliance has been tripped through running past a danger signal.

The lever 21 is also equipped with means for operating a whistle signal valve 51, 15 mounted on the top of the cab of the locomotive and connected by a suitable pipe 52 with the signal whistle 53. The valve 51, which is similar to the ordinary car discharge valve of the Westinghouse high speed brake and 20 signal equipment, is provided with a horizontal projecting member 54, which is adapted to be engaged by opposite resilient arms 55, preferably formed by a spring 56, secured at an intermediate point to a stem 57. The 25 stem 57, which is arranged at an angle to the lever, has an enlarged outer end or head 58, having a recess or seat to receive the intermediate attached portion of the spring 56. The recess or seat is concavely curved and 30 the stem and the arms form a substantially Y-shaped whistle operating device. One or the other of the arms of the whistle operating device will engage the whistle valve when the lever 21 is moved in either direction, and 35 when the lever is operated the brake will not only be applied, but the signal whistle will be blown and the electric light displayed. The light, which may be either white or colored, is preferably of the latter type to distinguish 40 it from an ordinary electric light.

Having thus fully described my invention, what I claim as new and desire to secure by Letters Patent, is:—

1. An automatic safety appliance for rail- 45 ways including a brake valve, a pivoted lever movable in either direction to open the valve and arranged to be retained in engagement with the valve by the air pressure to hold the valve open, and a tripping device 50 adapted to be moved into the path of the lever.

2. An automatic safety appliance for rail- 55 ways including an air brake valve, a pivoted lever movable in either direction to engage and open the valve and arranged to be maintained in engagement with the valve by the pressure of air, and means for automatically disengaging the lever from the valve to return the former to its initial position after 60 there has been a considerable reduction in the pressure of air.

3. An automatic safety appliance for rail- 65 ways including a brake valve, a spring for automatically closing the same, a pivoted lever movable in opposite directions to en-

gage and open the valve and arranged to be maintained in engagement with the said valve by the air pressure when the same is relatively high, and springs connected with the lever for disengaging the lever from the 70 valve to return the lever to its normal position and to permit the valve to close when the air pressure is relatively low.

4. An automatic safety appliance for rail- 75 ways including an air brake valve, a spring for automatically closing the same, a lever movable in either direction to engage and open the valve and arranged to be maintained in such engagement when air pressure is relatively high, and inclined springs arranged in 80 advance and in rear of the lever for disengaging the lever from the valve when the air pressure is relatively low.

5. An automatic safety appliance for rail- 85 ways including an air brake valve, and a piv- 90 otted lever having spaced portions arranged to engage and open the valve when the lever is moved in either direction, said valve being also provided with means coöperating with the engaged portions to maintain the lever in its engaged position.

6. An automatic safety appliance for rail- 95 ways including an air brake valve provided with a recess or seat, and an oscillatory lever having spaced projecting portions arranged to actuate and open the valve when the lever is moved in either direction, said projections being adapted to be carried into engagement with the seat to maintain the valve in its open position.

7. An automatic safety appliance for rail- 100 ways including an air brake valve having a seat, and an oscillatory lever provided with spaced engaging portions arranged to be carried into engagement with the seat to 105 limit the swing of the lever when the latter is moved in either direction, said lever being provided between the projecting portions with curved cam edges for opening the valve.

8. An automatic safety appliance for rail- 110 ways including an air brake valve, and an oscillatory lever having spaced projecting portions arranged to engage and open the valve and maintain the same in its open position, said lever being also provided with 115 spaced projecting arms arranged to limit the movement of the lever.

9. An automatic safety appliance for rail- 120 ways including an air brake valve, and an os- 125 cillatory lever having spaced projecting por- tions arranged to engage and open the valve and maintain the same in its open position, said lever being also provided with spaced projecting arms arranged to limit the movement of the lever, and opposite springs con- nected with the lever for automatically re- 125 turning the lever to its initial position.

10. An automatic safety appliance for rail- 130 ways including an air brake valve having a recess, a spring for automatically closing the

- valve, an oscillatory lever provided with spaced projecting portions arranged to open the valve and engage the recess thereof and adapted to be maintained in such engagement by relatively high air pressure, said lever being also provided with arms arranged to limit its movement, and opposite springs connected with the lever for disengaging the same from the valve to return the lever to its normal position and to permit the valve to close when the air pressure is relatively low.
11. An automatic safety appliance for railways including an air brake valve provided with a casing having upwardly projecting supports, a lever pivoted between the upwardly projecting supports and provided with depending diverging arms arranged to engage the casing to limit the movement of the lever, said lever being also provided with spaced projecting portions for engaging and opening the valve, and opposite springs connected with the lever for returning the same to its normal position.
12. An automatic safety appliance for railways including an air brake valve, a lever for opening the same, a signal whistle, a valve connected with the same, and means carried by the lever and arranged to engage and operate the signal whistle valve when the said lever is moved in either direction.
13. An automatic safety appliance for railways including a signal whistle, a valve connected with the whistle, an oscillatory lever, and spaced engaging portions carried by the lever and arranged to operate the valve when the lever is moved in either direction.
14. An automatic safety appliance for railways including a signal whistle, a valve connected with the whistle, an oscillatory lever, and resilient diverging arms carried by the lever and arranged to engage the valve and move when the lever is moved in either direction.
15. An automatic safety appliance for railways including a signal whistle, a valve connected with the whistle, an oscillatory lever, a stem extending from the lever and provided with an enlargement or head having a seat, and a spring secured at an intermediate point in the seat and having diverging arms arranged to engage and operate the valve when the lever is moved in either direction.
16. An automatic safety appliance for railways including an air brake valve, a lever arranged to engage and open the valve, and an electric circuit having an electric light and provided with circuit closing means arranged to be engaged and operated by the said lever.
17. An automatic safety appliance for railways comprising an automatic air brake valve, a pivoted lever movable in opposite directions to open the valve, and a circuit including an electric light, and circuit closing means located at opposite sides of the valve and located in the path of and adapted to be operated by the lever.
18. An automatic safety appliance for railways comprising an air brake valve, a casing for the valve, a pivoted lever movable in opposite directions to open the valve and provided with arms arranged to engage the casing for limiting the movement of the lever, and a circuit including an electric light, and opposite circuit closing devices arranged to be operated by the arms of the lever.
19. An automatic safety appliance for railways including an air brake valve, a lever movable in opposite directions to engage and open the valve, a circuit having an electric light and provided with circuit closing means arranged in the path of and adapted to be operated by the lever, a whistle signal valve, and means carried by the lever for engaging and operating the said whistle signal valve.
20. An automatic safety appliance for railways including an oscillatory lever, and a tripping device movable into and out of the path of the lever and having a yieldable portion for actuating the lever provided with means for automatically returning it to its normal position.
21. An automatic safety appliance for railways including an oscillatory lever, and a tripping device movable into and out of the path of the lever and having a pivoted member, and a spring connected with the pivoted member for yieldably maintaining the same in operative position and for automatically returning the pivoted member to its normal position.
22. An automatic safety appliance for railways including an oscillatory lever, and an approximately U-shaped pivoted tripping device having a pivoted side arranged to swing outward, and a spring connecting the pivoted side with the opposite side of the tripping device.
23. An automatic safety appliance for railways including an oscillatory lever, and a substantially U-shaped pivoted tripping device composed of a body portion, and a pivoted member arranged to swing outward, a lug extending from the body portion for limiting the outward movement of the pivoted member, and a spring connected with the pivoted member for holding the same normally at the limit of its inward movement.
24. An automatic safety appliance for railways including an oscillatory lever, a signal, a pivoted tripping device having a yieldable member provided with means for automatically returning it to its normal position, and means for communicating motion from the signal to the tripping device for

moving the same into and out of the path of the lever.

25. An automatic safety appliance for railways including an operating lever de-
5 signed to be carried by a train at the top thereof and provided with a loop extending from opposite sides of the lever, a semaphore, and a tripping device consisting of a lever pivotally mounted between its ends and
10 connected with the semaphore and movable

into and out of the path of the operating lever.

In testimony, that I claim the foregoing as my own, I have hereto affixed my signature in the presence of two witnesses.
